UNITED STATES PATENT OFFICE.

GEORGE E. THACKRAY, OF WESTMONT BOROUGH, PENNSYLVANIA.

DRAFT-RIGGING.

1,389,793.

Specification of Letters Patent.

Patented Sept. 6, 1921.

Application filed March 10, 1920. Serial No. 364,618.

To all whom it may concern:

Be it known that I, GEORGE E. THACKRAY, a citizen of the United States, and a resident of the borough of Westmont, county of 5 Cambria, and State of Pennsylvania, have invented certain new and useful Improvements in Draft-Rigging; and I do hereby declare the following to be a full, clear, and exact description of the invention, such as

10 will enable others skilled in the art to which it appertains to make and use the same.

My invention relates to improvements in draft rigging for mine or other cars with the object of simplifying and strengthening 15 the construction thereof.

In certain prior draft rigging devices the draw bar yoke has at the rear end a reduced section and it is therefore liable to breakage from the constant effect of buffing or pulling. This breakage not only ties up equipment and causes delay, but is a frequent source of damage and causes runaway cars, collisions, derailments, etc., with consequent 20 injury or destruction to men and materials. It is also more expensive to produce a yoke of the type mentioned with reduced rear portions, and economy and greater strength may be obtained by using a draw-bar yoke of constant section, thereby reducing the 25 tendency to break and eliminating the evil effects resultant therefrom.

I also provide an inner member of constant section, secured or riveted to the outer draw-bar yoke, and thereby produce a more rigid design and one better adapted to withstand the shocks and wear to which the parts are subjected from the constant buffing and pulling effects when in use.

My invention is particularly adapted to 40 mine or other cars made of metal and is so fashioned that a part of the car floor serves as a center sill, the latter providing a suitable receptacle for the draft rigging.

Having thus given a general description 45 of my invention, I will now, in order to make the matter more clear, refer to the annexed sheet of drawings, which forms part of this specification, and in which like characters refer to like parts.

50 Figure 1 is a vertical longitudinal sectional elevation taken on the line I—I of Fig. 2, showing my improved draft rigging and enough of the car to illustrate the application of my invention; 55 Fig. 2 is a top plane view of the draft rigging and a portion of the car body

to which it is secured; Fig. 3 is a vertical longitudinal sectional elevation similar to Fig. 1, showing a slightly modified form of my improved draft rigging; Fig. 4 is a 60 vertical transverse section taken on the line IV—IV of Fig. 3; Fig. 5 is a face view of one of the follower plates; and Fig. 6 is a vertical transverse section taken on the line VI—VI of Fig. 2.

65 Referring now to the characters of reference on the drawings:—1 is a part of the car body having the trough shaped central portion 2, over which is fastened at each end of the car the trough shaped reinforcing plate 3. The end sheet 4 of the car has mounted on it the bumper plate 5. The cheek plate 6 over the draw-bar and the draft gear supporting plate 8 have in them the holes 7 and 9 respectively in which the 70 reduced ends of the front follower block 10 and the rear follower block 11 fit and slide. The outer draw-bar yoke 12 and the inner member 13 are of substantially constant section throughout. The buffer 14 is a special shaped metal piece, the draw-head being an integral part thereof and is riveted to both the draw-bar yoke 12 and the member 13. 15 shows a type of corrugated spring plates adapted for use with this draft rigging, or if preferred, helical springs 19 may be used as shown in Fig. 3. Figs. 3 and 4 75 illustrate a modification in which the design is strengthened by the addition of the supporting plate 16, which has riveted there- 80 to the bottom cheek plate 17 provided with holes 18 in which the ends of the follower blocks 10 and 11 fit and slide.

85 The cheek plates themselves are provided with the slots 7 and 18 therein, and the end 90 portions of the same are securely riveted by a number of rivets to the car or supporting member and the central portion between the slots is also riveted so as to provide very substantial stops for the follower plates 95 and have a large number of rivets which are of greater strength than any buffing or pulling stresses to which the stop will be subjected, so that the construction is very substantial. The cheek plates are also of con- 100 siderable thickness to provide ample bearing and contact surfaces. The draft gear sup- 105 port plate as shown in Fig. 1 serves as a bot- 110 tom cheek plate but as illustrated in Fig. 3 this is supplemented by another stop plate 17, the construction and securing of which is similar to that of the upper stop plate 6.

It will readily be seen that my invention provides a firmly mounted draft rigging and since the draw-bar members are of constant section throughout, the full working strength 5 of the metal is available in every part of the draw-bar and particularly so at the inner end where the shocks are absorbed through the springs and thence conveyed to the car.

Although I have described and illustrated 10 my invention in considerable detail, I do not wish to be limited to the exact and specific details thereof as shown and described, but may use such modifications in, substitutions for, or equivalents thereof, as are 15 embraced within the scope of my invention, or as pointed out in the claims.

Having thus described my invention, what I claim and desire to secure by Letters Patent is:—

20. 1. In a draft rigging, a bar of U-shape having its free ends extending outwardly, another shorter bar bent into link-form and secured to and within the first mentioned

bar, the free ends of said shorter bar projecting inwardly toward each other, and a 25 draw-bar head and buffer abutting said free ends and secured to the aforesaid bars.

2. In a draft rigging, an outer U-shaped bar having its free ends extending outwardly in opposite directions, an inner U-shaped 30 bar secured to said outer bar and having its free ends extending inwardly in opposite directions, and an integrally formed draw-head and buffer secured to the sides of said bars.

3. In a draft rigging, a draw-bar recess, a draw-bar slidably mounted therein, and comprising a bar of U-shape having its free ends extending outwardly and another shorter bar bent into link form and secured 40 within the first mentioned bar, the free ends of said shorter bar projecting inwardly toward each other.

In witness whereof I hereunto affix my signature.

GEORGE E. THACKRAY.
